[57] CLAIM

The ornamental design for a water closet, as shown and described.

DESCRIPTION

FIG. 1 is a perspective view taken from the top, front and right side of a water closet embodying our new design;

FIG. 2 is a top plan view thereof;

FIG. 3 is a left side elevational view thereof, the right side being the mirror image of the left side; and,

FIG. 4 is a front elevational view thereof.

The fragmentary broken line representation of a wall in FIG. 1 is for purposes of illustration only and forms no part of the claimed design.

FIG. 4
